FLUIDIC SAFING-ARMING SYSTEM

This invention relates to an ordnance arming device and in particular to a pure fluid arming system.

The typical explosive weapon can be placed in either an armed or unarmed condition. In the armed condition the weapon will be detonated upon receipt of a firing impulse. Most firing devices are set to send a firing impulse upon the weapon being near or at a designated target. Typical firing impulse generating means are proximity devices, timer devices and impact devices. In the unarmed condition the weapon will not be detonated upon receipt of a firing impulse.

Great care must be exercised in using explosive weapons to maintain the weapon in an unarmed condition during launching and for a sufficient time after launching to protect the launching crew from detonation by the accidental receipt of a firing impulse. It is equally important that the weapon be armed as it approaches target so as to detonate in the vicinity of the target upon receipt of the target oriented firing impulse.

Modern weapon technology has undergone great advances in the last few years. It is no longer a rarity for a modern weapon carrying missile to operate from Mach one to Mach four velocities, undergo accelerations up to 20 g and altitudes up to 100,000 feet. The high speeds and altitudes of modern weapon carrying missiles have subjected the missile arming controls to shock, vibration, pressure and temperature extremes not previously known in older and slower missiles. The greater physical demands on arming systems have made electronic arming systems undesirable because of their inability to function effectively during severe missile vibrations, as would be found at Mach four velocities and accelerations of 20 g. Mechanical arming systems are adversely affected by wear and friction and are similarly undesirable because of the high tolerances required by component elements, and hence high cost.

Pure fluid systems have only recently been invented and rely on the interchange of momentum of two fluids to obtain a controlled output. Pure fluid devices are not adversely affected by vibrations and because no moving parts are required are easy to make at a nominal cost. The present invention utilizes pure fluid devices to arm a weapon carrying missile at a predetermined time, and hence distance, from the launching means.

Briefly, the present invention utilizes the ram air of the weapon carrying missile and the exhaust gases of the missile to provide two signals for a pure fluid arming system. Upon receipt of both signals a pure fluid circuit, after a predetermined delay, will send a fluid signal to an arming mechanism, carried by the missile, arming the missile for detonation upon receipt of a firing impulse.

It is therefore an object of the present invention to provide for the arming of a weapon-carrying missile at a safe distance away from the launching crew and before the missile reaches the target.

It is a further object of the present invention to provide means to arm a weapon carrying missile that is insensitive to missile speed, missile shock, missile vibration, and environmental temperature and pressure extremes.

Still another object of the present invention is to provide means to arm a weapon carrying missile utilizing

the ram air and exhaust gases of the missile and no external power source.

A further object of the present invention is to arm a weapon carrying missile upon receipt of plural signals.

Another object of the present invention is to provide means to accurately vary the delay time in a weapon carrying missile before arming the weapon.

Other objects, aspects and advantages of the present invention will clearly appear from the following description and from the accompanying drawing in which:

The drawing is a schematic illustration of a pure fluid arming device in accordance with the present invention.

- 15 In the drawing an arming circuit 100 is shown as being positioned outside a weapon carrying missile 10 that it is to arm. It is to be understood that normally the arming circuit is positioned inside the missile but is shown in FIG. 1 without missile 10 for illustrative purposes only. A ram conduit 13 leads to the nose 11, or any appropriate place, of missile 10 and is adapted to receive the ram air of the missile. Ram conduit 13 leads to left control 60 of a biased fluid amplifier 22. Biased fluid amplifier 22 has output conduits 24 and 25. The amplifier is biased to discharge from conduit 24 in absence of a fluid signal applied to control conduit 60. The bias could be accomplished by any of the conventional ways, such as setting the splitter to be closer to conduit 24, or as shown in U.S. Application Ser. No. 588,677 filed Oct. 19, 1966 by Elmer Swartz for a "Self-Biasing Fluid Amplifier," now U.S. Pat. No. 3,442,279. Line 23 is a schematic representation that the amplifier is biased to conduit 24 in absence of a fluid signal to control conduit 60.
- 20 25 Conduit 24 leads to ambient while conduit 25 leads to a binary counter 26 and acts as the pressure supply therefor. Binary counter 26 could consist of a number of stages and is any of the well known fluid binary counters that upon the simultaneous receipt of two pressure signals will, after a predetermined delay, emit a fluid signal. One commercial counter stage that could be used is made by the Corning Fluidic Devices department of Corning Glass and is identified by catalogue number FD-2712-Z-3211. Exhaust gases 14 by conduit 15 communicate with a check valve 16 which is positioned to direct flow from conduit 15 to conduit 18 but stop flow in the reverse direction. Conduit 18 leads to a stagnation tank 17. Stagnation tank 17 is an enclosed volume which serves to increase the static pressure of the fluid therein at the expense of the fluid velocity in a manner well known in the art. A conduit 40 communicates stagnation tank 17 with a pressure regulator 41. Pressure regulator 41 could be any of the conventional pressure regulators or an orifice plate. An orifice plate is merely a plate with a small orifice in the middle of it. Flow is directed against the plate and the size of the orifice determines the amount of fluid to be passed through the plate. The fluid not passed through the orifice is vented to ambient. A conduit 19, by a regulator 20 and a conduit 21, supplies exhaust gases to the power nozzle (not shown) of biased amplifier 22. Regulator 20 could be an orifice plate as regulator 41 and serves to reduce the pressure to biased amplifier 22. A conduit 42 communicates pressure regulator 41 with AND unit 43. The AND unit could be any one of the well known units now commercially available. AND unit 43 has output conduits 44, 45 and 90. A con-

duit 52, along with conduit 42 supplies the fluid signals to the unit. Upon receipt of fluid from only conduit 52 AND unit 43 will discharge fluid to the ambient by conduit 90. If only conduit 42 sends fluid to AND unit 43 the fluid will be discharged from conduit 44 while if fluid is supplied to the AND unit by conduits 42 and 52 the AND unit will discharge fluid from conduit 45. Conduit 45 leads to a pressure-actuated switch 46 which, when activated, serves to complete an electrical circuit which will arm the missile. Obviously any type of pressure triggered arming means could be used and the use of an electrical circuit is for illustrative purposes only. Conduit 44 leads to a fluid oscillator 48 which has a left output conduit 49 and a right output conduit 50, the latter which is communicated to atmosphere. Conduit 49 serves to communicate the oscillator to conduit 51 which serves to supply fluid to binary counter 26 along with conduit 25. Because of the fluctuations in the pressure and temperature of the exhaust gases it is desirable that the frequency of oscillator 48 be insensitive to both pressure and temperature changes. It is therefore preferable that the oscillator be built in accordance with U.S. Application Ser. No. 595,538 filed Nov. 18, 1966 by Carl J. Campagnudo et al., for a "Pressure and Temperature Insensitive System," now U.S. Pat. No. 3,504,691.

When missile 10 is in its launching means a plug could be put in ram conduit 13 and connected to the launching pad by a string. This would prevent a burst of wind from entering ram conduit 13 and supplying a false signal to the arming circuit. Before launching, the rockets will be firing and exhaust gases will be gathered and directed by conduit 15 through check valve 16 by conduit 18 to tank 17. Conduit 19 will direct fluid, by regulator 20 and conduit 21, to biased amplifier 22. The fluid will initially be vented out conduit 24 because of the built in bias. No fluid will be received by ram conduit 13 when the missile is in its launching means to overcome the bias means. Conduit 40 will direct exhaust gases from tank 17 to regulator 41 which will reduce the pressure of the exhaust gases for AND unit 43. If an orifice plate is used for regulator 41 the size of the orifice can be varied to control the pressure of fluid directed to AND unit 43. The AND unit will receive one signal from conduit 42, when the missile is in the launching means, and will therefore direct fluid to conduit 44. Since no ram fluid is received by control conduit 44, conduit 25 will not direct fluid to binary counter 26. The binary counter requires two signals to direct fluid to conduit 52, and since only conduit 51, as will be seen, will direct fluid to the counter, no fluid signal will be supplied to conduit 52. Fluid directed to conduit 44 will enter fluid oscillator 48 where it will alternately be discharged from conduit 49 and conduit 50, the latter conduit communicated to atmosphere. Conduit 49 will direct fluid to binary counter 26 by conduit 51. The binary counter will not direct fluid to conduit 52 since a second fluid signal will not be directed to the binary counter by conduit 25. Arming switch 46 will not be activated since AND unit 43 will not direct pressure to conduit 45, as the AND unit will direct fluid to conduit 44 upon receipt of a signal from conduit 42 alone. When the missile leaves the launching means the plug in the end of ram conduit 13 will be removed by the string attaching it to the launching means allowing ram air to enter ram conduit 13 and communicate to control conduit 60 of biased amplifier

22. This will switch the output of biased amplifier 22 to conduit 25 which will direct fluid to binary counter 26. Conduit 51 will continue to direct fluid to binary counter 26 during actual flight combining with conduit 25 to give the necessary two signals to the binary counter. The binary counter, after an appropriate delay will, by conduit 52, direct a signal to AND unit 43 which will be also receiving a signal from conduit 42 giving the unit the necessary plural signals to direct fluid to conduit 45 and to pressure arming switch 46. The switch will be activated completing an electrical circuit which will arm the missile.

10 The delay time (t) for the binary counter to send an arming signal to AND unit 43 is determined by the following formula:

$$t = 2(n/f)$$

20 where n is the number of counter stages and f is the oscillator frequency. Since the oscillator frequency is insensitive to temperature and pressure fluctuations it can be seen that by using a predetermined number of counter stages and a particular oscillator frequency a desired time delay can be obtained.

25 It can readily be seen that we have provided a simple means to arm a weapon carrying missile away from the launching means after a designated time delay.

We claim as our invention

1. In a weapon carrying missile powered by exhaust gasses an arming system, comprising:
  - a means for receiving a portion of said exhaust gas;
  - a means for receiving ram air;
  - a fluid amplifier supplied with a source of power fluid having a control conduit connected to said means for receiving ram air, said amplifier having first and second output conduits and including means to direct said power fluid out said first conduit in the absence of ram air and out said second output conduit upon the application of ram air to the system;
  - an AND gate having two input conduits and at least two output conduits; one input of said AND gate being connected to said means for receiving exhaust gas;
  - a fluidic oscillator having an input conduit connected to one of said output conduits of said AND gate so that said oscillator is rendered operative when exhaust gas only is applied to said AND gate;
  - a fluidic binary counter connected to said second output conduit of said fluid amplifier such that said counter is rendered operative upon the application of ram air to the system, and connected to an output of said fluid oscillator, the oscillations of which are counted by said counter;
  - means connecting said binary counter to the other of said inputs of said AND gate for directing a signal to said AND gate after said counter has counted a predetermined number of oscillations; and
  - a pressure-activated switch for arming said missile connected to the other of said outputs of said AND gate so that it will receive a pressure signal upon the coincidence of input signals to said AND gate.
2. A device according to claim 1 wherein said fluid oscillator has a frequency and includes means to render said frequency insensitive to changes in temperature and pressure of said exhaust gases.

- 3. A device according to claim 1 wherein said power fluid for said amplifier is said exhaust gases.
- 4. A device according to claim 3 wherein:
  - a. said exhaust gases are communicated to a stagnation tank, and
  - b. a conduit communicates said stagnation tank and said amplifier.
- 5. A device according to claim 4 wherein a conduit communicates said stagnation tank with said AND unit.
- 6. A device according to claim 5 wherein a pressure regulator is placed in said conduit which communicates said stagnation tank and said AND unit.
- 7. A device according to claim 4 wherein a pressure regulator is placed in said conduit communicating said stagnation tank and said amplifier.
- 8. In a weapon carrying missile, an arming system, comprising:
  - a. a pressure activated means for arming said missile;
  - b. a means associated with said missile for receiving a plurality of fluid signals; and
  - c. a fluid circuit means for actuating said pressure-activated means in response to and a predeter-

- 5 mined time after the coincidental receipt of said plurality of fluid signals, said fluid circuit means including a delay means in which all the operating elements are stationary except for the working fluid for determining the length of the time period between the receipt of said plurality of fluid signals and the actuation of said pressure-activated means.
- 9. The arming system of claim 8 in which said delay means is a fluidic timing circuit.
- 10. The arming system of claim 9 in which said fluidic timing circuit comprises a fluidic binary counter, means for initiating the operation of said counter upon the application of one of said plurality of fluid signals to said arming system, and a fluidic oscillator providing a signal to be counted by said binary counter upon the application of another of said plurality of signals.
- 15. 11. The arming system of claim 8 utilized in a missile powered by exhaust gasses in which said plurality of fluid signals comprises a portion of said exhaust gas and ram air.
